UNITED STATES PATENT OFFICE.

FRANK E. THOMPSON, OF CORRY, PENNSYLVANIA, ASSIGNOR TO CORRY CASTOR COMPANY, OF CORRY, PENNSYLVANIA, A CORPORATION OF PENNSYLVANIA.

CASTER.

1,016,654.

Specification of Letters Patent.

Patented Feb. 6, 1912.

Application filed November 11, 1911. Serial No. 659,675.

To all whom it may concern:

Be it known that I, FRANK E. THOMPSON, a citizen of the United States, residing at Corry, in the county of Erie and State of Pennsylvania, have invented certain new and useful Improvements in Casters, of which the following is a specification, reference being had to the accompanying drawings.

10 This invention relates to improvements in casters and particularly to improvements in casters provided with pintle-retaining means and adapted for use in metallic bedsteads the legs of which are tubular; and an 15 object of this invention is to simplify and strengthen the construction of the pintle-retaining means of such casters to reduce the cost of manufacture of the same and to increase the durability and efficiency there- 20 of.

In the drawings illustrating the principle of this invention and the best mode now known to me of applying that principle, Figure 1 shows my new caster in elevation; Fig. 2 is a section on the line A—A of Fig. 1; Fig. 3 is a plan view of my new caster; Fig. 4 is a section on the line B—B of Fig. 3, the caster-wheel being shown omitted; Fig. 5 is a view looking in the direction of 30 the arrow X in Fig. 1, the caster-wheel being shown omitted; Figs. 6 and 7 are details showing the pintle-retaining centering-plates; Fig. 8 is a view similar to Fig. 4 and shows a modification in which the pintle 35 is detachably retained; and Fig. 9 is a section on the line C—C of Fig. 8.

The caster proper (that is, apart from the pintle-retaining means) is of the kind commonly found in the type of casters known 40 as "point bearing" casters and consists of the usual caster-wheel *a*, jaws *b*, yoke *c* and pintle *d*, the upper end of the latter being formed with a groove *d'* and a pointed upper end or pivot-point *d''*. The base-plate 45 *e* is formed with the usual central hole *e'* through which passes the pintle *d*. Upon the base-plate *e* there are mounted two pintle-retaining centering-plates *f*, *g* each of which is formed with a pair of lugs *h* at 50 its lower end and with a centrally-disposed pintle receiving channel *i*. In the top of the plate *g* there is formed a notch or recess *j* and from the top of the central channel *i*

in the plate *f* there extends a recess or notch *k*. The plates *f*, *g* are interlocked with each other by forcing the top of the plate *g* into the notch *k*, the top of the plate *f* being thereby made to enter the notch *j* in the top of the plate *g*. Thus, the plates *f*, *g* are securely and firmly interlocked and a strong structure produced. These plates *f*, *g* are arranged diametrically of the base-plate *e* and are fastened therein by passing the lugs *h* through slots in the base-plate *e* and then upsetting the lugs. In the top of 65 the channels *i* there is mounted a circular or disk-like bearing-plate *m* against which bears the upper pointed or pivot end *d''* of the pintle *d*. The disk obtained by punching the central hole *e'* in the base-plate *e* may 70 be used as the bearing-plate *m*. The pintle *d* is retained in the channel *i* by forcing out the metal of the walls of the latter in one of the centering plates, in the form of lugs *n* into the groove *d'* in the upper end 75 of the pintle. The pintle-retaining centering-plate *f* is formed at its top with an upwardly-extending lug *o* which passes through a central hole formed in the top or base of the inverted U-shaped leaf-spring *p* and which is upset to fasten the latter to the plate *f*. The legs *p'* of the spring *p* are adapted to press outwardly in the usual manner against the inner face or wall of the tubular leg *q* of the bedstead and thereby to retain the caster detachably within 85 the same.

When it is desired to hold the pintle detachably in the centering-plates, one of the latter, as *g'*, is formed with a recess *r* which 90 extends from the central channel *i* and in which is sprung a curved leaf-spring *s*. The latter bears yieldingly against the wall or bottom of the groove *d'* and thereby retains the pintle detachably within the centering-plate.

It is to be observed that the pintle *d* is firmly supported by being given a bearing throughout practically the whole length of the edge portions along the channels *i*.

To strengthen the base-plate *e*, it is formed with radial ribs *e''*; but this stiffening or strengthening of the base-plate is regarded by me as a well-known mechanical expedient.

To make easy and smooth the entrance of

the retaining-plate into the tubular leg q , the lateral edges of the centering-plates are slightly tapered, as is best shown in Fig. 4.

I claim:

- 5 1. A pintle-retainer for casters having a base-plate; a centering-plate the bottom edge of which extends centrally across said base-plate and has a bearing upon the pintle; and spring-arms carried by said centering-plate and arranged to engage the inner wall of the tubular leg of the bed.
- 10 2. A pintle-retainer for casters comprising a base-plate; a pair of centering-plates the bottom edges of which extend centrally across said base-plate and one of which has a bearing upon the pintle; and spring-arms carried by one of said centering-plates and arranged to engage the inner wall of the tubular leg of the bed.
- 15 3. A pintle-retainer for casters having a base-plate formed with a hole for the passage of the pintle; a centering-plate the bottom edge of which extends centrally across said base-plate and is formed with a recess which lies above the hole in the base-plate; and spring-arms carried by said centering-plate and arranged to engage the inner wall of the tubular leg of the bed; said centering-plate having a bearing upon
- 20 4. A pintle-retainer for casters comprising a base-plate formed with a hole for the passage of the pintle; a pair of centering-plates the bottom edges of which extend

centrally across said base-plate and are 35 formed with recesses which lie above the hole in said base-plate and one of which has a bearing upon the pintle; and spring-arms which are carried by one of said centering-plates and which are arranged to engage the tubular wall of the leg of the bed. 40

5. A pintle-retainer for casters comprising a base-plate; a pair of centering-plates the bottom edges of which extend centrally across said base-plate and are interlocked 45 and one of which has a bearing upon the pintle; and spring-arms carried by one of said centering-plates and arranged to engage the inner wall of the tubular leg of the bed and to work in recesses of which 50 said centering-plates form walls.

6. A pintle-retainer for casters having a base-plate; a centering-plate the bottom edge of which extends centrally across said base-plate and which has a bearing upon 55 the pintle and is formed with means for retaining the latter; and spring-arms carried by said centering-plates and arranged to engage the inner wall of the tubular leg of the bed. 60

In witness whereof I hereunto set my hand at Corry, Pennsylvania, this sixth day of November, 1911, in the presence of the two undersigned witnesses.

FRANK E. THOMPSON.
